TERMINAL FOR ELECTRIC DISCHARGE
TUBES

George E. Shoemaker, Ithan, Pa.

Application January 14, 1948, Serial No. 2,167

13 Claims. (Cl. 176—122)

1

This invention relates to electric discharge tubes and more particularly to terminals and fittings for supporting such tubes and carrying current thereto. Heretofore such tubes have customarily been provided with exposed contact members at their ends. As such tubes are frequently installed for operation in series in high voltage circuits it is desirable to reduce the hazard of electrical shock to a minimum.

The primary object of the present invention is to make possible the safe operation of hot and cold cathode tubes at relatively high voltages, and this end I accomplish by providing means for electrically connecting and mechanically supporting a tube in relation to a base having wires leading to a source of current supply, such means being so designed that no live part is accessible to human fingers.

Another object of the invention is to provide terminal fittings of the character referred to which are compact and inexpensive to manufacture and consist of a minimum of parts and yet permit a tube to be readily and quickly connected to its supporting base or disconnected therefrom.

Another object of the invention is to provide terminal fittings of this character which are so designed as to allow for a substantial movement of a tube in the direction of its axis without exposing any live part, or disconnecting the lamp mechanically or electrically.

Other objects of the invention and advantages to be gained by the use thereof, including its compliance with proposed or existing electrical codes, will be more apparent from the description of a preferred embodiment of the invention, and a modification thereof, which follows hereinafter having reference to the accompanying drawings, whereof:

Fig. 1 represents a side elevation of one end portion of an electric discharge tube with a terminal fitting and a base for supporting the fitting and carrying current thereto, such elements being constructed and assembled in accordance with my invention;

Figs. 2, 3 and 9 represent vertical cross sections of the same, taken respectively as indicated by the arrows II—II, III—III and IX—IX of Fig. 1;

Fig. 4 represents a longitudinal section of the same taken as generally indicated by the arrows IV—IV of Fig. 2, but showing portions of certain elements in side elevation;

Fig. 5 represents an exploded perspective view showing the two halves of the terminal fitting;

Fig. 6 is a view taken similarly to Fig. 1, but showing a modified form of tube, terminal fitting

2

and base, certain parts being broken away for clearness of illustration;

Fig. 7 is a perspective view of the terminal fitting shown in Fig. 6;

Fig. 8 is a perspective view of the link which connects the base and terminal fitting shown in Fig. 6; and

Fig. 10 is an enlarged perspective view of one end of a prong of said link.

- 10 In the embodiment of the invention illustrated in Figs. 1 to 5 and 9 of the drawings the end portion of electric discharge tube of conventional form is represented at 1. Within the tube is an electrode 2 which joins a conducting wire 3. The electrode 15 2 may be either a coil filament as illustrated or a conventional shell type electrode. Affixed to the end of the tube 1 in surrounding relation to it is a terminal fitting 4 having a cylindrical bore 5 within which the tube is snugly fitted and secured. 20 The terminal fitting is also provided with a socket 6 which parallels the bore 5. In its preferred form the socket 6 is of square or rectangular cross section. Near the inner end of the socket 6 a contact member 7, which may take the form of a metallic plate, is provided. The contact member 25 7 joins the conducting wire 3.

- A desirable method of assembling the tube 1 and its terminal fitting 4 is to make the terminal fitting of two counterpart sections, as most clearly illustrated in Fig. 5, which are cemented or otherwise joined together at their meeting faces 8. The terminal fitting may be made of glass, porcelain or other material having suitable insulating properties with the conducting wire 3 30 embedded between the two sections at their meeting faces. At the top of the terminal fitting 4 a keyway 9 is formed which is adapted to engage a key 11 in the base 12 upon which the lamp is supported. By thus keying together the tube 1 35 and its base 12 allowance is made for substantial relative movement between these elements in the direction of the axis of the tube and at the same time lateral displacement of one such element with respect to the other is prevented.

- 40 In the drawings only a portion of the base 12 is shown. It may be assumed that where a number of tubes 1 are connected together in series, at the ends of the line of tubes thus connected base members 12 would be employed which would have 45 a single socket 13, and that at intermediate points in the line base members would be employed having two such sockets 13. Such intermediate base members would include a second half at the left hand as viewed in Fig. 1, which would be in all respects similar to the right hand portion shown

in the drawings except that the socket would extend in the opposite direction whereby the series of tubes would be maintained in a straight line. The socket 13 is preferably of square or rectangular cross section and, like the socket 6, has near its inner end a contact member 14 joined to a conducting wire 15. The base members 12 may be secured to a ceiling, such as represented at 16, or to any other structure upon which it may be desired to mount a tube, by means of flanges 17 and screws 18. Conveniently the base member 12 is also made of two counterpart sections of insulating material joined together at their meeting faces 19 and with the conducting wire 15 embedded between the two sections. Obviously the keyway 8 and key 11 may be reversed as between the terminal fitting 4 and base 12, or these elements may be engaged in sliding contact with capacity for limited relative movement by other means than that represented in the drawings.

A link 20 electrically connects and mechanically supports the terminal fitting 4 of the tube 1 in relation to the base 12. In its preferred form the link 20 has two prongs 21, 22 of square cross section designed to fit within the sockets 13 and 28, respectively. A conducting wire 23 is embedded within the link 20 and exposed only near the ends of its prongs 21, 22. When the prongs 21, 22 are fully inserted within the sockets 13 and 6, the ends of the conducting wire 23 engage the contact members 14 and 7 completing the electrical circuit between the source of current supply and the tube or tubes to be energized. The ends of the wire 23 make positive engagement with members 14 and 7 by means of resilient contact members 30 and 31, biased toward the center line of the link.

In its preferred form the link 20 is formed with a ring 24 which serves as a convenient finger hold whereby the link may be readily inserted within or withdrawn from the sockets 6 and 13. Desirably the link 20 is attached to the base 12 by means of a chain 32 to prevent its complete detachment therefrom. The chain 32 is of such length that when the link 20 is withdrawn to the limit of the chain, the link is completely withdrawn from the socket 6, but not completely withdrawn from the socket 13, so that the lamp 1 may be removed without dislodging the link from its association with the base 12.

The base 12, as shown most clearly in Fig. 9, is provided with a cavity 33 having therein a vertically movable detent 34 urged downwardly by a spring 36. At its downward limit of movement the shoulder 37 of the detent 34 blocks the socket 13 and the lower end 38 projects downwardly from the base 12. When the fitting 4 is brought into engagement with the base 12, as illustrated in Fig. 9, the detent 34 is forced upwardly against the spring 36, unblocking the socket 13 to permit access of the prong 21 of the link 20. With the fitting 4 removed, the link 20 when withdrawn to the limit of its movement as permitted by the chain 32 can be reinserted only as far as the detent which is located sufficiently remote from the live contact member 14 to prevent arcing the wire 23. In this position the exposed contact member 31 of prong 22 cannot become energized. It will be observed that the sockets 6 and 13 are relatively deep and too narrow for insertion of a finger so that there is no occasion or possibility, with any normal use of the device of my invention, for the person installing or removing a lamp to receive an electric shock.

In the modified form of the invention illustrated

in Fig. 6 of the drawings, wherein all parts which remain unchanged are given the same reference numerals as above, the tube 1a, its terminal fitting 4a, and the base 12a for supporting it are all right-angled in shape. This arrangement has an advantage in that a number of lamps may be serially arranged in juxtaposed relation without any appreciable intervening gap between each lamp, thus providing continuous illumination across a ceiling. In this form of the invention the terminal fitting 4a includes an end portion 25 which caps the extremity of the tube 1a and spaced annular portions 26 which surround the body of the tube 1a to engage and support the same. In its intermediate areas the terminal fitting 4a is cut away, thus permitting maximum illumination at the ends of the tubes and preventing overheating thereof. The base member 12a is formed to complement the shape of the terminal fitting 4a and to allow two tubes 1a to be mounted in proximate relation. As in the case of the first form of the invention the conducting wires 3a and 15a are wholly insulated and unexposed except near the inner ends of the sockets 8a and 13a.

The link 20a, as shown clearly in Fig. 8, is similar to link 20 except that its lower prong 22a is slotted, as indicated at 27, to surround a contact member 7a within the socket 6a and thus form an electrical connection with a terminal of the conductor 23a disposed within the slot 27. The upper prong 21a of link 20a is provided with a contact member 30a, as represented in Fig. 10, which is biased toward the center line of the link, but when inserted within the socket 13a is flattened by its engagement with the lower wall thereof. The contact member 7a is recessed in the slot 27 to a depth which is so related to the voltage of the circuit that there is no possibility of flashover to anything external to or at the mouth of the slot 27. In this modification there is therefore no need for the detent 34, as the wire 23a may be energized without creating an electrical shock hazard.

It will be noted that both forms of my invention are characterized by their compactness, the provision for end play between the lamp and the base member which supports it, and the capacity for the tube to be quickly installed or released. The single moving part consists of a link which can be readily grasped and which as soon as it is partially removed from the sockets within which it is accommodated offers no opportunity for contact with any live part. By virtue of the shape of its prongs the link assists the key and keyway in resisting lateral displacement as between the tube and its supporting base, while permitting relative movement in the longitudinal direction of the tube.

The permissible endwise movement of the tube relative to the base members is substantial in the sense that it is of the order of one-half inch or more. Such allowance for endwise movement without interrupting the electrical connection between the tube and base member is considerably greater than the permissible movements involved in other forms of safety terminals. It avoids the necessity of providing a rigid spacing member or channel running for the length of the tube.

Although I have shown and described herein two specific embodiments of my invention it will be readily apparent that various changes may be made in the form of the lamp, its terminal fitting, the base for supporting the lamp and the key for connecting and assembling these elements; and that certain features of the invention may

be used to advantage without the use of other features; all without departing from the spirit of the invention as defined in the annexed claims.

Having thus described my invention, I claim:

1. In combination, an electric discharge tube, a base, and a link for electrically connecting and mechanically supporting said tube in relation to said base, said tube and said base each having therein a socket and a conductor with a portion exposed within said socket and otherwise insulated, said sockets being relatively deep and narrow whereby the exposed portions of the conductors are inaccessible to human fingers, and said link having prongs adapted to fit within said sockets and having a conductor embedded within the link and exposed only at areas where said prongs contact the conductors of said tube and base.

2. In combination, an electric discharge tube having a terminal fitting at an end thereof, a base, and a link for electrically connecting and mechanically supporting said terminal fitting in relation to said base, said terminal fitting and base each having therein a socket and a conductor exposed within said socket and otherwise wholly embedded within the fitting or base, said sockets being relatively deep and narrow whereby the exposed portions of the conductors are inaccessible to human fingers, and said link having prongs adapted to fit within said sockets and having a conductor embedded within the link and exposed only at areas where said prongs contact the conductors of said fitting and base.

3. The invention set forth in claim 1 in which the link is further characterized by a finger hold in the form of a ring and the prongs are formed integrally with said ring.

4. The invention set forth in claim 1 in which the sockets and the prongs fitting therein are polygonal in cross section.

5. The invention set forth in claim 1 in which means are provided for preventing detachment of the link from the base.

6. The invention set forth in claim 1 in which

means are provided for limiting outward movement of the link from the socket of the base to prevent its complete withdrawal from said socket.

7. The invention set forth in claim 1 in which means are provided for blocking the socket of the base whereby, when the link is partially withdrawn from said socket, said blocking means prevent its reinsertion to establish contact with the conductor leading to said socket, said blocking means including an element adapted to be engaged by the tube and rendering the blocking means inoperative when such engagement occurs.

8. The invention set forth in claim 1 in which the link has a prong which is interiorly recessed at its end, with a contact member housed within said recessed end, and the socket accommodating said prong has a companion contact member adapted to enter the recessed end of the prong.

9. The invention set forth in claim 2 in which the terminal fitting and base are each made of a plurality of sections of insulated material joined together with their conductors embedded in the meeting faces of the joined sections.

10. The invention set forth in claim 2 in which the terminal fitting has a cylindrical bore accommodating an end of the tube, said bore paralleling the link-receiving socket of said fitting.

11. The invention set forth in claim 2 in which the base and terminal fitting have means to prevent lateral displacement, while permitting substantial relative endwise movement between said elements.

12. The invention set forth in claim 2 in which the end of the tube, its terminal fitting and the base for supporting it are all right-angular.

13. The invention set forth in claim 2 in which the end of the tube and its terminal fitting are right angular, the fitting capping the extremity of the tube and engaging the body thereof in surrounding relation and being cut away in the intermediate areas.

GEORGE E. SHOEMAKER.
